UNITED STATES PATENT OFFICE

100,012

DESIGN FOR A STOVE

Henry L. Ford, Kingsport, Tenn., assignor to
Eastman Kodak Company, Rochester, N. Y., a
corporation of New York

Application November 14, 1935, Serial No. 59,568

Term of patent 14 years

To all whom it may concern:

Be it known that I, Henry L. Ford, a citizen of the United States of America, residing at Kingsport, in the county of Sullivan and State of Tennessee, have invented a new, original, and ornamental Design for Stoves, of which the following is a specification, reference being had to the accompanying drawing, forming a part thereof in which:

Figure 1 is a perspective view of a stove show-

ing my new design with a portion of the handle member shown in broken lines.

Figure 2 is a plan view thereof with the handle member omitted therefrom.

I claim:

The ornamental design for a stove, as shown and described.

Signed at Kingsport, Tennessee, this 6th day of November, 1935.

HENRY L. FORD.
